BASKETBALL REBOUND DOME

Kenneth E. Hayden, 2568 Jaycox Road,
Avon, Ohio 44011

Filed Jan. 26, 1973, Ser. No. 326,989

Term of patent 14 years

Int. Cl. D21—01

U.S. Cl. D34—5 VV

FIG. 1

FIG. 2

FIG. 3

FIG. 4

FIG. 5

FIG. 6

FIG. 7

FIG. 1 is a perspective view of a basketball rebound dome showing my new design;

FIG. 2 is a right side view of the device shown in FIG. 1;

FIG. 3 is a left side view of the device shown in FIG. 1;

FIG. 4 is a front view of the device shown in FIG. 1;

FIG. 5 is a rear view of the device shown in FIG. 1;

FIG. 6 is a top view of the device shown in FIG. 1; and

FIG. 7 is a bottom view of the device shown in FIG. 1.

I claim:

The ornamental design for a basketball rebound dome, as shown and described.
